US0D1107635S

(12) **United States Design Patent** (10) Patent No.: **US D1,107,635 S**
 Mao et al. (45) Date of Patent: ** Dec. 30, 2025

(54) **EQUIPMENT CASE**(71) Applicant: **Anhui Hangcheng Intelligent Technology CO., LTD**, Wuhu (CN)(72) Inventors: **Xingyou Mao**, Wuhu (CN); **Kai Fu**, Wuhu (CN); **Jia Zhang**, Wuhu (CN)(73) Assignee: **Anhui Hangcheng Intelligent Technology CO., LTD**, Wuhu (CN)(**) Term: **15 Years**(21) Appl. No.: **29/953,651**(22) Filed: **Jul. 23, 2024**(30) **Foreign Application Priority Data**

Jun. 27, 2024 (CN) 202430397564.8
 (51) LOC (15) Cl. **12-16**
 (52) U.S. Cl.
 USPC **D12/423**; D3/273; D3/294
 (58) **Field of Classification Search**
 USPC D3/273, 294, 905; D12/423
 CPC B60R 9/055; B60R 5/04
 See application file for complete search history.
